UNITED STATES PATENT OFFICE.

JOSHUA T. FISK, OF ADRIAN, MICHIGAN, ASSIGNOR TO GEORGE P. FISHER, JR., TRUSTEE, OF CHICAGO, ILLINOIS.

AUTOMATIC SELECTING APPARATUS AND SYSTEM.

SPECIFICATION forming part of Letters Patent No. 763,972, dated July 5, 1904.

Application filed January 8, 1902. Serial No. 88,850. (No model.)

To all whom it may concern:

Be it known that I, JOSHUA T. FISK, a citizen of the United States, and a resident of Adrian, county of Lenawee, Michigan, have invented 5 certain new and useful Improvements in Automatic Selecting Apparatus and Systems, of which the following is declared to be a full, clear, and exact description.

My invention relates to selecting apparatus 10 for use in connection with telephonic, telegraphic, or signaling systems and to the adaptation of such an apparatus to a number of telephone-stations on the same line by which any one station may be signaled from a central office or from any other station.

The objects of my invention are, first, to provide an improved form of step-by-step selecting device and an operating impulse-transmitter therefor which will be simple in construction, effective in operation, and which may be returned to zero position without necessitating resort to changes in strength or polarity of the current on the selector-operating circuit; second, to provide means whereby 25 the forward and return movements of the selecting device may be effected by the operation of a single magnet; third, to adapt such an apparatus for use in connection with different telephone-stations in the same line by 30 which any one may be signaled from a central office or from any other station and by which the stations not called or signaled may be locked out by the operation of the selecting devices; fourth, to adapt the improved selecting 35 devices to such a telephone-circuit in such a manner that the telephone and selector-operating circuits may be of any suitable arrangement, may be independent of each other, if desired, and operated by either central or 40 local energy; fifth, to provide means whereby the return of the selecting devices to zero or home position will be effected by the operation of the automatic telephone-switches, and to provide other automatic means whereby the 45 apparatus and the system may be rendered convenient and certain in operation, the conversation between connected stations secret and free from liability to be disturbed by calls from other stations on the line.

In the drawings, Figure 1 is a view in vertical elevation of my improved selecting and transmitting apparatus as adapted for use at a telephone-station, the inclosing casing being shown in cross-section. Fig. 2 is a view in vertical section of the same with the casing 55 removed and with certain parts broken away. Fig. 3 is a view in horizontal section of my improved impulse - transmitter or circuit-breaker, taken on the line 3 3 of Fig. 2. Fig. 4 is a detail view, in vertical section, taken on the line 4 4 of Fig. 3 and looking in the direction of the arrow. Fig. 5 is a detail plan view of the selecting apparatus and parts controlled thereby. Fig. 6 is a detail view, in vertical elevation, of the selector-wheel and lock for 60 the automatic telephone-switch. Fig. 7 is a detail view, in vertical section, of the circuit-closer for the signaling-circuit. Fig. 8 is a view in vertical section of the governor-controlled releasing mechanism for the selecting 65 device. Fig. 9 is a diagrammatic view of the selective device and the operating means therefor. Fig. 10 is a diagrammatic view of a number of telephone-stations, illustrating an arrangement of my improved selecting apparatus and system. Figs. 11 and 12 are diagrammatic views of other arrangements for 70 the selector-operating circuit.

Impulse-transmitter or circuit-breaker for the selector-operating circuit.—The transmitter is mounted upon a suitable base-board 10 and within a suitable inclosing casing 11. The frame of the transmitter comprises the circular plates 12 and 13, spaced apart and secured to one another by the shouldered pins 80 or rods 14, and is supported in position on the base-board 10 by the offsets or legs 15 of the plate 13.

The circuit-breaker for the transmitter comprises a notched disk *a*, loosely mounted upon 90 a shaft 16 and arranged to engage a vibrating arm *b*, pivotally mounted on an offset of the plate 13. The free end of the arm *b* is provided with a stud *b'* of vulcanized fiber or other suitable insulating material, arranged 95 to engage one of a pair of spring-contacts *c* and *d*, located in the selector-operating circuit. The spring-contacts *c* and *d* are mount-

ed upon a block 17 of insulating material, which is held in position by a piece 18, secured to the plate 12 of the transmitter-frame by the shouldered offset pins 19. A bent 5 spring-stop *e* is secured to one of the rods 14 and is arranged to engage with the notches of the disk *a*. This disk is driven in one direction by the operating-shaft 16 through a one-way connection comprising a ratchet-wheel 10 20, fixed to the shaft, and a spring-pressed pawl 21, fixed to the disk.

The operating-shaft 16 is provided with shouldered journals at either end engaging suitable bearings formed in the frame-plates 15 12 and 13. The forward end of the shaft extends through an opening in the casing 11 and is provided at its outer end with an operating-handle 22. The handle 22 is arranged to play over the face of a dial 23, held in position to close the opening in casing 11 by means of shouldered offset pins 24, secured to the frame-plate 12. A coiled volute spring 25 is secured at one end to the operating-shaft 16 and at the other end to one of the 20 fixed pins 24, which after being wound up by the forward movement of the handle 22 serves as power-propelling means for the shaft 16 during its return movement. The forward movement of the shaft 16 is variably limited by a stop-pin 26, arranged to engage the handle 22. A circular series of holes 27 are located in the disk 23 and are spaced at equal distances apart to correspond with a given number of notches of the disk *a*. 25 In the present construction each space between any two adjacent holes corresponds to three of the notches of the disk, so that by placing stop-pin 26 in any one of the holes 27 and by moving the operating-handle to engage the pin the circuit-breaker will be operated during the return movement of the shaft 16 to transmit three impulses or any multiple of three, as desired. The disk is provided opposite the holes with indicating numbers or 30 names, as shown, corresponding to the various signals or stations to be selected.

Means are provided for arresting the return movement of the operating-shaft and the circuit-breaker at different predetermined 35 points—namely, both just before it reaches and at the normal position of the operating-shaft, so that the succession of impulses transmitted may be followed by an additional impulse. For this purpose a bent stop-arm 28 of the peculiar formation indicated in the drawings is fixed to the shaft 16, and an end projection thereon normally engages a home or stop pin 29, being held in such position by the tension of the operating-spring 25. This 40 pin 29 is mounted on an arm 30, pivoted to the frame-plate 12 and adjustably fixed in position by a threaded pin engaging a slot in said arm, as clearly indicated in Fig. 4. A combined movable stop and locking pin 31 for 45 engaging the arm 28 is mounted upon the free

end of a bell-crank 32, which is pivoted to an arbor 33, extending between the frame-plates 12 and 13. A coiled spring 34 extends between one of the pins 14 and an arm 35, fixed to the shaft or arbor 33, which spring tends 50 to move the arm 32 and pin 31 into the position indicated by dotted lines in Fig. 2. In this position the pin 31 will engage a laterally-projecting lug 36 upon the arm 28 to arrest the return movement of the shaft and 55 arm in advance of the normal or home position, as indicated by dotted lines in Fig. 2. Means such as hereinafter described are, however, provided for normally holding the arm 32 in the position indicated by full lines with 60 the pin 31 in engagement with the hooked end of the arm 28, by which the operating-shaft 16 is locked with arm 28 in its normal position against the home or stop pin 29. In this position also the pin 31 will serve to arrest the further return movement of the arm 28 in normal position, and with the precise construction indicated there is no absolute necessity for employing the home or stop pin 29. I, however, prefer to employ such a 65 home stop in order to relieve the arm 32 and operating parts from the strain of the operating-spring 25.

In order that the succession of impulses may be transmitted uniformly and distinctly, 70 governing or retarding means are provided for controlling the return movement of the operating-shaft. Such means have previously been connected either directly to the shaft or directly to the circuit-breaker. I, however, prefer to independently operate the retarding device through a one-way connection comprising a ratchet-wheel 37, fixed to the shaft 16 and engaging a pawl 38, fixed to a gear 39, loosely mounted on the shaft adjacent the 75 fixed ratchet-wheel. The gear 39 is arranged to operate through the medium of a suitable train of gears 40, 41, and 42, a fan-governor 43, or other suitable retarding device. The fan-governor and gear-train are mounted upon 80 arbors or shafts suitably journaled in the frame-plates 12 and 13. By thus independently operating the retarding device the movement of the shaft 16 and circuit-breaking disk *a* may be arrested, while the governor is free 85 to move on until arrested by friction, thus relieving the parts from unnecessary wear and strain.

Selecting device.—Upon the base-board 10 is mounted a suitable support 44 for the selecting instrument and the operating mechanism therefor. A step-by-step selecting device, preferably in the form of a wheel *f*, provided with ratchet-teeth, is suitably journaled within bearings upon the support 44. A pin 45, upon the face of the wheel *f*, is arranged to engage a home stop 46 upon an upright 47, secured to the support 44. A coiled spring 48 is secured at one end to a pin in the support 44 and at the other end to a flexible 50

connection 49, wound about and secured to the shaft of the step-by-step wheel f . By this means the selective device is normally held in home position with the pin 45 in engagement with the stop 46. An operating-electromagnet g is mounted adjacent the step-by-step wheel f and is provided with a spring-pressed balanced armature 50, pivoted to bearings on the support 44. A laterally-projecting bent arm 51 is secured to the armature 50 and is provided at its outer end with a pivoted spring-pressed feed-pawl 52. The upper end of the upright 47 is provided with a laterally-projecting stop 53, which serves to limit the forward movement of the feed-pawl, and an oppositely-arranged stop-pin 54 is adjustably threaded on the upper end of the upright 47 and serves to engage a tailpiece on the pawl 52 to throw the latter out of engagement with the teeth of wheel f upon the rearward movement of the armature 50. A spring-pressed retaining-pawl 55, pivoted to bearings on the support 43, is arranged to engage the teeth of the step-by-step ratchet f . By this means the step-by-step selector f may be variably moved against the tension of the spring 48 in accordance with the number of vibrations of the armature 50.

Governor-controlled means are provided whereby the retaining-pawl may be thrown out of engagement to permit the return of the selector f to its home or zero position. This means consists of a compound hit-and-miss governor controlled by the vibrations of the armature of magnet g and comprises a freely-vibrating balanced arm 56, pivotally mounted upon the upper end of a swinging upright 57 and a freely-vibrating knocker 58, pivotally mounted upon an upright 59, intermediate the armature 50 and the vibrating arm 56, as shown in Figs. 8 and 9. The free inner end of the arm 56 is hooked, as at 59', for normally engaging the upper end of the vibrating armature 50. The swinging upright 57 is pressed by a spring 62', (see Fig. 5,) coiled about its pivot 62 toward the position shown by dotted lines in the diagrammatic Fig. 9 against a stop 60, adjustably threaded through the upper end of an upright 61, and its pivot-pin 62 is provided near one end with a projecting lug 63, arranged to engage a corresponding lug or tailpiece 64 of the retaining-pawl 55. The upright 59 is adjustably secured to the support 44, so that it may be moved nearer to or farther away from the armature 50 of the magnet g . When the armature 50 is vibrated by successive electrical impulses passing through the magnet g , it strikes successively against the knocker 58 and the latter strikes against the freely-vibrating arm 56 and serves to hold it in elevated position disengaged from the armature 50 until the successive electrical impulses cease. The arm 56 then falls with its hooked end 59' into engagement with the ar-

mature 50, and a single additional movement of the armature will serve to release the retaining-pawl 55 in the manner hereinafter described. An upright 65 is provided with a hooked upper end arranged adjacent the free end of the vibrating arm 56. (See Fig. 8.) This upper hooked end is positioned just above the end of the arm 56 when the latter is drawn toward the magnet g by the armature 50; but when the armature 50 permits the arm 57, together with the lever 56, to be drawn away from the magnet g by the spring 62' the hooked end of upright 65 is no longer above the freely-vibrating arm 56. By this arrangement the hooked end of upright 65 prevents the disengagement of the arm 56 from armature 50 during a single movement of the latter, but will not interfere with such disengagement during successive vibrations of the armature.

Lockout mechanism and signaling devices for the telephone-stations.—In the application of my improved selecting apparatus to telephone-stations located upon the same line one of the improved selecting devices will be located at each of the stations and all preferably arranged in a common operating-circuit. A single impulse-transmitter or circuit-breaker may, if desired, be located at a central office, so that any of the stations on the line may be signaled therefrom; but my improved form of transmitting apparatus is particularly designed to be employed at each of the stations, so that any one of the subscribers may call any of the other subscribers. In the latter case, as indicated in the drawings, both the selecting device and the impulse-transmitter or circuit-breaker will be located within the same inclosing casing 11 upon the upper end of the base-board 10, which also forms the support for the telephone set. A receiver-supporting automatic switch or hook h of ordinary construction is pivoted to an upright 66 on the support 44 of the selecting instrument, is provided with an operating-spring 67, and projects in the usual manner outside of such casing, as indicated in Fig. 1. The hook or switch h carries a laterally-projecting stud 68, of insulating material, which is arranged to engage and operate the set of spring-contacts i, j and k, l of the telephone-circuits. These contacts and circuits may be of any desired arrangement; but preferably the contact k is arranged to engage a spring-contact m , by which the signal-operating circuit is closed at this point; but will be opened as soon as the receiver is removed from its hook in the well-known manner. These contacts are preferably mounted upon a block 69, of insulating material, upon the support 44, as shown in Fig. 2.

A connecting-rod 70 is pivoted at one end to the upper arm of the bell-crank 32 and passes upwardly through an opening in the support 44 and loosely through a laterally-

projecting ear 71 upon the tailpiece of the automatic switch *h*. The upper end of the rod 70 is threaded and provided with lock-nuts 72', adjustable thereon and engaging the ear 71, thus forming a loose one-way connection between the bell-crank 32 and the automatic switch or telephone-hook *h*. By this means the combined lock and stop pin 31 on bell-crank 32 is controlled by the movement of the automatic switch and normally held in the position indicated by full lines in Fig. 2 when the receiver is placed upon its support. By adjusting lock-nuts 72' the throw of the lock and stop-pin 31, effected by the movement of switch *h*, may be adjusted.

An upright 70' is fixed to the support 44, and to the bent upper end portion thereof is pivoted intermediate its ends an arm *n*, the lower half of which is heavier than the upper half, so that it normally tends to swing into an upright position against a stop-pin 71' on the upright 70'. When so located, the bent upper end of the arm *n* is in position to engage a laterally-projecting pin 72 upon the tailpiece of the automatic switch *h*, (see Fig. 6,) and the arm *n* thus serves as a lock to prevent the movement of the switch to operate the contacts *i* *j* and *k* *l* of the telephone-circuits. The locking-arm *n* is, however, normally held out of operation by a trip-pin *o* on the selecting-wheel *f*, which when the selecting-wheel is in home position engages a V-shaped cam portion 73 on the lower end of the arm and holds the latter in the position shown in Fig. 1, so that the switch may operate to close the telephone-circuits. The selecting-wheel *f* is provided with a second trip-pin *p*, which is arranged to engage with the V-shaped portion 73 of the arm and to hold the lock out of operation in a similar manner after the selective wheel has been moved through a predetermined distance. The pin *p* is placed at a different position on the selecting-wheels at each of the stations, so that when the selectors are operated in response to a succession of impulses from any one of the circuit-breakers the arm *n* will be in position to lock the telephone-switches *h* in all of the stations except the one corresponding to the number of impulses which have been transmitted over the operating-circuit, at which station the selecting-wheel will have moved to bring its trip-pin *p* into position to hold the locking-arm *n* out of operation. The arm *n* also serves as a switch for the signal-operating circuit and for this purpose is provided with a laterally-projecting pin 74, which is arranged to engage a spring-strip *r*, fixed to a block 75 of insulating material on the support 44. The pin 74 engages with the spring-contact *r* whenever the arm *n* is held in the position shown in Fig. 1 when either the trip-pin *o* or the trip-pin *p* engages the V-shaped cam portion 73 of the arm; but in the upright position of the arm (shown in Fig. 6)

the contact between the pin 74 and spring *r* is broken. The cam-shaped portion 73 is so shaped that the arm *n* will be held with its upper end out of the path of the pin 72 and its pin 74 in engagement with the spring-contact *r* when either of the trips *o* or *p* is in any one of a limited number of positions adjacent the cam portion, so that the telephone-switch at the "called" station will be unlocked and the circuit closed through the signal thereat with certainty even though the feed-pawl may skip one or two steps. In the present construction the trips *o* and *p* will effect the operation of the arm *n* when they occupy any one of three positions adjacent the cam portion 73. The apparatus illustrated in the drawings is designed for use at station 5, and the arm *n* thereat will be operated whenever fifteen impulses are transmitted over the selector-operating circuit even if the operating device for the selecting-wheel should skip one or two steps. This arrangement will not interfere with the selecting of the other stations, since, as previously stated, the circuit-breakers are designed to transmit only three impulses or some multiple of three in accordance with the different stations on the line.

Another circuit-closer is interposed in the signal-operating circuit and comprises a contact-pin *s*, adjustably threaded in the upper end of but insulated from an upright 76 on the support 44. The pin *s* is thus located in the position to make electrical contact with the arm 51 on the armature 50 whenever the latter is moved toward the left, as shown in Fig. 7.

Circuits and operation.—In Figs. 10, 11, and 12 I have illustrated diagrammatically three stations, Nos. 1, 2, and 3, each provided with transmitting and selecting apparatus. As previously stated, the apparatus may be used with any desired arrangement of circuits; but I prefer to provide independent selector-operating and telephone circuits. The operating-circuit may be either normally closed or normally opened. The wiring for a normally closed operating-circuit is illustrated in Figs. 10 and 11, in which figures, however, the circuit is shown in the condition when station No. 1 has just called station No. 3. In Fig. 12 the wiring for a normally opened circuit is illustrated, but in this instance, as in Figs. 10 and 11, the circuit is shown in the condition when station No. 1 has just called station No. 3. In Fig. 10 the operating-magnets *g* are located in series and are normally closed, operating line 77, which may be traced as follows: from battery 78 to the support-contacts *c* and *d* of the impulse-transmitter and to the operating-magnet of station No. 1, from thence to the contact *c* and *d* of the operating-magnet of station No. 2 and then to the contacts of the impulse-transmitter and operating-magnet at station No. 3. From thence line-circuit 77 extends in a similar manner to

the other stations on the line and back to battery 78 by the ground or by a metallic return-wire. With such an operating-circuit the position of stop 29 and the throw of stop 31 are so adjusted that in the normal or home position of the operating-shaft 16 the circuit-breaking disk *a* will be held in the position shown in Fig. 2, with the spring-stop *e* engaging one of the notches and with the vibrating arm *b* resting on its periphery. In this position of the arm *b* the contacts *c* and *d* will be brought into engagement, as indicated in Fig. 2 and at stations Nos. 2 and 3 in Fig. 10, and the operating-circuit will be normally closed—that is, when none of the stations are calling—through the actuating-magnets *g*, so that normally, as shown in Figs. 1, 2, 5, 8 and by full lines in Fig. 9, the armature 50 will be drawn up, the feed-pawl 52 and the detaining-pawl 55 will be thrown out of engagement with the selecting-wheel *f*, the latter will be held in normal or home position by its spring 48, with the trip *o* normally holding the locking-arm *n* out of operation and the circuit through the signaling devices will be broken at contact-pin *s*. The automatic switches are depressed in the well-known manner by the weight of the receivers and through the medium of connecting-rod 70 and bell-crank 32 will hold the pin 31 into engagement with the hooked end of the arm 28, thus locking the transmitting-shaft 16 and handle 22 in normal position. When a subscriber at any one station desires to call any other station, the operation will be as follows: In the diagrammatic Fig. 10, No. 1 is the calling station, No. 3 is the called station, and No. 2 is an intermediate station. The receiver at calling station No. 1 is removed from its support, switch *h* is depressed, connecting that station to the line, and bell-crank 32 is released and is moved by its spring 34 to disengage the lock-pin 31 from engagement with the hooked end of arm 28. The operating mechanism for the circuit-breaker at station No. 1 is thus released. The pin 26 will be placed in the hole 27 of the indicating-disk 23 opposite the number corresponding to the station to be called, in this instance station No. 3. The handle 22 will then be moved into engagement with the stop-pin 26 and released. As soon as the arm 28 is moved away from stop-pin 31 the latter, together with bell-crank 32, will be further moved by spring 34 into the position shown by dotted lines in Fig. 2 and by full lines at station No. 1 in Fig. 10. During the return movement of the operating-shaft the circuit-breaker will be operated to transmit the proper number of impulses to operate all of the selecting devices on the line through a predetermined distance. As previously described, the return movement of the operating-shaft 16 will be arrested by the engagement of the stop-arm 28 with the pin 31 just before it reaches its normal position, as indicated by dotted lines in Fig. 2 and by full lines at station No. 1 in Fig. 10. By this means the circuit-breaking disk *a* will also be arrested before it has completed its traverse and in such position that the vibrating arm *b* will engage with one of the notches of the disk and the contact-springs *c* and *d* will be held open, thus breaking the operating-circuit at this point, so that the armature 50 of each of the operating-magnets *g* on the line will be released, as shown in Fig. 10. By thus arresting the movement of the circuit-breaker before it completes its traverse and so that the operating-circuit is broken it will be impossible for the conversation between calling-station No. 1 and called station No. 3 to be interrupted by the transmission of signals from any other station. At called station No. 3 the pin *p* of the selector will be in position to move the arm or signal-switch *n* into engagement with the spring-contact *r*, and the circuit through the automatic bell *t* or other suitable signaling device may then be traced as follows: from local battery 79 by wire 80 to contacts *h* and *m*, by wire 81 to contact *r* through the arm *n* and the supporting-frame to the armature 50, by contact *s* and wire 82 to the bell *t*, and by wire 84 back to the battery 79. The signal will then be operated until the automatic switch *h* is actuated by the removal of the receiver to connect the telephone at station No. 3 to line, which operation is rendered possible, since the upper end of the locking-arm *n* is moved out of the path of the pin 72 on the switch. At all other stations, however, as soon as the selectors are moved the arm *n* will be swung by gravity into an upright position out of engagement with the contact *r* and with its upper end in the path of the pin 72, as indicated at station No. 2, thus locking the telephone-switch *h* and breaking the circuit through the signaling device. By thus locking the switch *h* against movement the removal of locking-pin 31 from the hooked end of stop-arm 28 and the manipulation of the circuit-breaker will be prevented. During the transmission of the succession of impulses over the operating-line the hit-and-miss governing device comprising the freely-vibrating arm 56 and the freely-vibrating knocker 58 intermediate the arm 56 and the armature 50 will operate to hold the arm 56 in an elevated position, as indicated by dotted lines in Fig. 9, and the upright 57 will be forced by its spring into engagement with the stop 60, thus permitting the retaining-pawl 55 to engage with the teeth of selecting-wheel *f*. Similar governing devices have been heretofore used; but instead of a freely-vibrating part, as arm 56, some form of retarding device has been connected directly to the operating-arm. In such constructions it is necessary that the vibrations of the armature of the actuating-magnet shall be maintained at a sufficient high rate of speed to hold the vibrating part out of operation. In my form of hit-

and-miss governor, comprising three vibrating parts, it is only necessary that the product of the vibrations of any two of them will not be divisible by the number of vibrations of the third in order that the arm 56 shall be effectively held out of operation. The speed of vibration, therefore, for the actuating-armature 50 may be comparatively slow to operate the feed-pawl 52 with certainty and without skipping. By adjusting the arm 59 to and from the armature 50 the operation of the hit-and-miss governor may be regulated to effectually operate with any desired speed of vibration of the armature. As soon, however, as the transmission of impulses ceases and the armature 50 comes to rest in the position shown by dotted lines in Fig. 9 the hooked end 59' of the arm 56 will drop into engagement with the upper end of the armature. When conversation is finished, the receiver at the called station will be replaced upon its hook, thus shifting the stop 31 through the medium of connecting-rod 70 and bell-crank 32 to the position shown in full lines in Fig. 2 and permitting the operating parts for the circuit-breaker to be returned completely to normal or home position by its actuating-spring 25 and to be again arrested with the arm 28 in contact with the stop 29. This movement of the operating-shaft 16 will advance the disk α one-half a tooth, and thereby move the arm b to bring the contacts c and d into engagement and transmit an additional impulse. The circuit will thus be closed through all of the operating-magnets g , the armatures will be drawn up, and the feed and retaining pawls 52 and 55 will be thrown out of engagement with the selecting-wheels f , permitting the latter to be returned to normal by the springs 48, with the trip-pins o in operative engagement with the arms n , as shown in Fig. 1. At the same time the spring-contact 51 upon armature 50 is moved away from its contact s , and the signal-operating circuit at each station is broken at this point. The system will then be in condition for the transmission of any subsequent call over the line.

As previously stated, the telephone-circuits may be of any desired arrangement; but I prefer that the telephones at the different stations shall be arranged in normal open multiple arc branches, either legged from a single line to the ground or connected to two wires 85 and 86 of a metallic circuit, as shown in Fig. 10. Preferably, also, the local batteries 79 are arranged to be closed through the automatic signaling-bell and through the primary of the transmitter by the operation of the automatic switches h . This arrangement of circuits is clearly indicated in Fig. 10, is of well-known construction, and need not be more fully described.

In Fig. 11, in which the parts are shown in the position assumed when station No. 1 has just

called station No. 3 I have illustrated a modified arrangement, in which the operating-circuit 77 is closed through a series of relay-magnets u . The operating-magnets g are located in normal open circuits energized from local batteries 87, and these circuits are controlled by the operation of the armatures 88 of the relay-magnets u . With this arrangement of the operating-circuit it is necessary that the throw of the stop-pin 31 and the position of the stop 29 shall be so adjusted that the movement of the circuit-breaker will be arrested by the pin 31 in closed position and that the disk α be moved forward through the space of one tooth when the stop 31 is removed. By this movement of the circuit-breaking wheel through the distance of one tooth the operating-circuit through the relay-magnets u will be momentarily opened and the local circuits through the actuating-magnets g closed to restore the selecting devices to normal. The operation is otherwise the same as previously described.

In the open-circuit arrangement (shown in Fig. 12, in which the parts are shown in position assumed after station 1 has just called station 3) the operating-magnets g are connected in series or in branches 89 between conductors 90 and 91, the wire 90 is connected at one end to the battery 78, and the wire 91 is provided with branches 92 at each station, either legged to the ground or to a common return-wire 93, in which branches the normally open make-and-break contacts c and d at each station are located. With this arrangement the throw of the stop-pin 31 and the position of the home stop 29 are so adjusted that the movement of the circuit-breaking disk will be arrested in position to close the contacts c and d (as at station 1) and so that the further movement of the disk when the stop-pin 31 is removed will open the contacts c and d and restore the line to normal condition. As indicated in Fig. 12, with an open circuit the magnets g are located upon the opposite side of the pivots of armatures 50. The construction and operation in other respects is the same as that already described in connection with the closed operating-circuit. (Shown in Fig. 10.)

It is obvious that various other modifications in the arrangement of the operating and telephone circuits may be employed, that the improved selecting and transmitting apparatus may be used in other connections for various purposes, and that numerous changes may be made in the construction and operation of the parts by the skilled mechanic without departure from the essentials of the invention.

Having described my invention, what I claim as new, and desire to secure by Letters Patent, is—

1. In a selective apparatus, the combination with a switch for the telephone-circuit and with a selecting device, of electrical means

- for variably moving said selecting device, a movable locking-arm for said switch and trips carried by said selecting device arranged to control said locking-arm.
5. 2. In a selective apparatus for telephones, the combination with a switch for the telephone-circuit, of a movable lock for said switch and a variably-movable selecting device having means arranged to engage said lock and hold the same out of operation both in a normal position of said selecting device and after the movement thereof through a predetermined distance.
10. 3. In a selective apparatus for telephones, the combination with an automatic switch for the telephone-circuit, of a pivoted locking-arm for said switch, a step-by-step selecting-wheel having trip-pins arranged to hold said locking-arm out of operation, both in the normal position of said selecting-wheel and after the movement thereof to a predetermined position and means for variably actuating said selecting-wheel.
15. 4. In a selective apparatus for telephones, the combination with a switch for telephone-circuit, of a lock for said switch, a step-by-step selecting device having trips arranged to hold said locking-arm out of operation, both in the normal position of said selecting device and after the movement thereof to a predetermined position, means for variably actuating said selecting device from its normal position and means for releasing the same to permit its return in the opposite direction to normal.
20. 5. In a selective apparatus, the combination with a step-by-step selecting device, of a signal, an actuating-switch therefor, and an abutment mounted on the selecting device arranged to actuate said switch after the movement of said selecting device to any one of a limited number of adjacent predetermined positions.
25. 6. In a selective apparatus for telephones, the combination with a lock-out for the telephone-circuit, of a step-by-step selecting device arranged to shift said lock-out to an inoperative position after a movement to any one of a limited number of adjacent predetermined positions.
30. 7. In a selective apparatus for telephones, the combination with an automatic switch for telephone-circuits and with an electric signal, of a lock for said switch and a step-by-step selecting device arranged to hold said lock in an inoperative position and to close the circuit through said signal after a movement to any one of a limited number of adjacent predetermined positions.
35. 8. In a selective apparatus for telephones, the combination with an automatic switch for the telephone-circuits and with a signal, of a lock for said switch, a step-by-step selecting device arranged to control said lock and said signal and means for variably stepping said selecting device to different predetermined positions.
40. 9. In a selective apparatus for telephones, the combination with an automatic switch for the telephone-circuit and with a signal, of a lock for said switch, a step-by-step selecting device, means for variably actuating said selecting device to different predetermined positions and trips carried by said selecting device arranged to release said lock and to actuate said signal. 70
45. 10. In a selective apparatus for telephones, the combination with an automatic switch for the telephone-circuit, of a movable lock for said switch, a selecting device arranged to hold said lock out of operation both in its normal position and after the movement thereof to a predetermined position and a signal controlled by the movement of said lock. 75
50. 11. In a selective apparatus for telephones, the combination with an automatic switch for the telephone-circuit and with an electric signal, of a movable arm constituting a lock for said telephone-switch and a controller for the signal-circuit, a step-by-step selecting device, trips carried thereby arranged to control said movable arm, and means for variably actuating said selecting device. 80
55. 12. In a selective apparatus, the combination with a selecting device and with an impulse-transmitter for the selector-operating circuit, of a movable stop for holding said impulse-transmitter against movement, a movable lock controlled by said selecting device and mechanical controlling connections between said lock and said movable stop. 85
60. 13. In a selective apparatus, the combination with a selecting device and with an impulse-transmitter for the selector-operating circuit, of a movable stop arranged to hold said impulse-transmitter against movement, a lock, mechanical controlling connection between said lock and said movable stop and a trip carried by said selecting device arranged to normally hold said lock out of operation. 90
65. 14. In a selective apparatus for telephones, the combination with a selecting device, an impulse-transmitter for the selector-operating circuit and with an automatic receiver-supporting switch for the telephone-circuit, of a stop controlled by the movement of said switch arranged to hold said impulse-transmitter against operation and a lock for said switch controlled by said selecting device. 95
70. 15. In a selective apparatus for telephones, the combination with a selecting device, an impulse-transmitter for the selector-operating circuit and with an automatic switch for the telephone-circuit, of an operating-handle for said impulse-transmitter, a movable stop connected to said switch arranged to hold said handle against movement, a lock for said switch and a trip carried by said selecting device arranged to normally hold said lock out of operation. 100
75. 16. In a selective apparatus, the combination with an electric signal, of a circuit-closer 105
80. 17. In a selective apparatus, the combination with an electric signal, of a circuit-closer 110
85. 18. In a selective apparatus, the combination with an electric signal, of a circuit-closer 115
90. 19. In a selective apparatus, the combination with an electric signal, of a circuit-closer 120
95. 20. In a selective apparatus, the combination with an electric signal, of a circuit-closer 125
100. 21. In a selective apparatus, the combination with an electric signal, of a circuit-closer 130

for the signal-circuit, a selecting device arranged to control said signal-circuit closer, an operating-magnet for said selecting device, a second circuit-closer for the signal-circuit controlled by the armature of said magnet, a switch for the telephone-circuit and a third circuit-closer for the signal-circuit controlled by said telephone-switch.

17. In a selective apparatus for telephones, the combination with an automatic switch for the telephone-circuit and with an electric signal, of a combined lock for the automatic switch and circuit-closer for the signal-circuit, a selecting device having trips arranged to actuate said combined lock and circuit closer both in the normal position of said selecting device and after the movement thereof to a predetermined position, an operating-magnet for said selecting device and a second signal-circuit closer controlled by the armature of said magnet.

18. In a selective apparatus, the combination with a selector and with an actuating-magnet therefor, of a step-by-step device operated by said magnet in response to a succession of uniform electrical impulses for advancing said selector in one direction, a retractor for returning said selector in the opposite direction to normal, means operated directly by the armature of said magnet for tripping said retractor into operation and means for holding said trip out of operation during and at the end of the succession of electrical impulses.

19. In a selective apparatus, the combination with a selector having a series of uniform ratchet-teeth and with an operating-magnet therefor, of a feed-pawl actuated by the armature of said magnet in response to a succession of uniform electrical impulses for advancing said selector step by step in one direction, a retaining-pawl for said selector, a trip for said retaining-pawl, means controlled by said operating-magnet arranged to hold said trip out of operation during and at the end of the succession of electrical impulses and operate the same in response to a single additional impulse, and a retractor for returning said selector in the opposite direction to normal.

20. In a selective signaling apparatus, the combination with a selector having a series of uniform ratchet-teeth and with an operating-magnet therefor, of a step-by-step device operated by said magnet in response to a succession of uniform electrical impulses, a releasing-trip for said selector, means for coupling said releasing-trip directly to the armature of said magnet and means for holding said coupler out of operation during the successive vibrations of the armature of said magnet.

21. In a selective apparatus, the combination with a selector, of propelling devices for advancing said selector from its normal position, governor-controlled means arranged to

return the same thereto comprising a freely-vibrating arm and means actuated by the operation of said propelling devices for holding said freely-vibrating arm out of operation.

22. In a selective apparatus, the combination with a selector, of an operating-magnet therefor arranged to advance said selector from its normal position, governor-controlled means for returning the same thereto comprising a freely-vibrating arm and means operated by the successive vibrations of the armature of said magnet for holding said freely-vibrating arm out of operation.

23. In a selective apparatus, the combination with a selector, of an actuating-magnet for advancing said selector from its normal position, means for returning the same thereto, and a governor for controlling said means comprising a freely-vibrating arm and a freely-vibrating knocker actuated by the armature of said magnet.

24. In a selective apparatus, the combination with a step-by-step selector and with an actuating-magnet therefor, of means operated by said magnet for advancing said selector in one direction, means for releasing said selector to permit it to return to the opposite direction to normal and a governor for controlling said means comprising a freely-vibrating arm and means for holding said arm out of operation during the successive vibrations of the armature of said magnet.

25. In a selective apparatus, the combination with a selector, of a propelling-magnet for advancing said selector in one direction, a release-trip for said selector, a coupler for connecting said release-trip directly to the armature of said magnet comprising a vibrating arm, means for holding said vibrating arm out of operation during the successive vibrations of said armature and a retractor for said selector.

26. In a selective apparatus, the combination with a selector, of a propelling-magnet for advancing said selector in one direction and governor-controlled means for effecting the return of said selector in the opposite direction to normal comprising an arm shiftable in different paths at an angle to each other, the armature of said magnet being arranged by successive movements to vibrate said arm in one path to hold it out of operation and by a single vibration to shift said arm in the other path to effect the return of said selector.

27. In a selective apparatus, the combination with a selector, of a propelling-magnet for advancing said selector in one direction, devices for effecting the return of said selector in the opposite direction to normal, a vibrating arm normally coupling said return-effecting devices directly to the armature of said magnet and means for holding said vibrating arm out of operation during the successive vibrations of said armature.

28. In a selective apparatus, the combination with a selector, of a propelling-magnet for advancing said selector in one direction, means for effecting the return of said selector in the opposite direction to normal and a coupler arranged to normally connect said return-effecting devices directly to the armature of said magnet, said armature being arranged to hold said coupling devices out of operation during its successive vibrations and to operate said return-effecting devices through the medium of said coupler by a single additional movement.
29. In a selective apparatus, the combination with a selector, of a propelling-magnet for advancing said selector in one direction, means for effecting the return of said selector in the opposite direction to normal comprising a movable part and a vibrating arm pivoted to said movable part and arranged to couple said part to the armature of said magnet and means for holding said coupling-arm out of operation during the successive vibrations of said armature.
30. In a selective apparatus, the combination with a selector, of a propelling-magnet for advancing said selector in one direction, means for effecting the return of said selector in the opposite direction to normal comprising a pivoted spring-held part and a vibrating governor-arm pivoted to said part and arranged to couple the latter directly to the armature of said magnet and means for holding said coupling-arm out of operation during the successive vibrations of said armature.
31. In a selective apparatus, the combination with a selector, of a propelling-magnet for advancing said selector in one direction, a retaining-pawl for said selector, a trip for said retaining-pawl, a movable part connected to said retaining-pawl, a vibrating arm pivoted to said movable part and arranged to couple the latter directly to the armature of said magnet, means for holding said coupling-arm out of operation during the successive vibrations of said armature and a retractor for said selector.
32. In a selective apparatus, the combination with a selector, of a propelling-magnet for advancing said selector in one direction and governor-controlled means arranged to effect the return of said selector in the opposite direction to normal comprising a vibrating actuating-arm arranged to engage the armature of said magnet and be operated by a single movement thereof and a vibrating knocker intermediate said armature and said vibrating arm for holding the latter out of operation during the successive vibrations of said armature.
33. In a selective apparatus, the combination with a selector, of a propelling-magnet for advancing said selector in one direction in response to a succession of electrical impulses, of governor-controlled means for effecting the return of said selector in the opposite direction to normal comprising a movable part, a freely-vibrating arm pivoted to said movable part and arranged to couple the latter to the armature of said magnet, and a freely-vibrating knocker intermediate said armature and said vibrating arm for holding the latter out of operation during the successive vibrations of said armature.
34. In a selective apparatus, the combination with a selector, of a propelling-magnet for advancing said selector in one direction, governor-controlled means for releasing said selector to permit it to return in the opposite direction to normal comprising a freely-vibrating arm arranged to couple said release directly to the armature of said magnet and a freely-vibrating knocker intermediate said armature and said vibrating arm for holding the latter out of operation during the successive vibrations of said armature and a retractor for said selector.
35. In a selective apparatus, the combination with a step-by-step selector having ratchet-teeth, of a propelling-magnet therefor, a feed-pawl actuated by said magnet in response to a succession of electrical impulses for advancing said selector in one direction, a retaining-pawl for said selector, governor-controlled means for releasing said retaining-pawl comprising a movable part and a vibrating arm pivoted to said part and arranged to couple the latter directly to the armature of said magnet, means for holding said coupling-arm out of operation during the successive vibrations of said armature and a retractor for said selector.
36. The combination with a selector and with an operating-circuit therefor, of a power-propelled impulse-transmitter for said circuit, means for variably actuating said impulse-transmitter, means for arresting the operation of said impulse-transmitter an invariable predetermined distance before and at the end of its traverse, whereby a succession of electrical impulses may be followed by an additional impulse, means acting in response to the succession of impulses for variably actuating said selector from normal position and means acting in response to the additional impulse for effecting the return of said selector to normal.
37. The combination with a selector and with an operating-circuit therefor, of a power-propelled impulse-transmitter for said circuit, means for variably actuating said impulse-transmitter, stop devices automatically acting to arrest the operation of said impulse-transmitter an invariable predetermined distance before and at the end of its traverse, whereby a succession of impulses is followed by an additional impulse, an actuating-magnet for said selector, means operated by said magnet in response to a succession of impulses for moving said selector in one direction and means operated in response to an additional impulse.

for effecting the return in the opposite direction to normal.

38. The combination with a selector and with an operating-circuit therefor, of an impulse-transmitter for said circuit, a reciprocating part, power-driven and arranged to operate said impulse-transmitter during its return movement, means for variably determining the forward movement of said part, means for arresting the return movement of said part, an invariable predetermined distance in advance of and at its normal position, whereby a succession of impulses is followed by an additional impulse, means acting in response to the succession of impulses for variably actuating said selector from normal and means acting in response to the additional impulse for effecting its return to normal.

39. In selective systems for telephones, the combination with a selector and with an operating-circuit therefor, of an impulse-transmitter for the selector-operating circuit, an automatic switch for the telephone-circuit, means controlled by the movement of said switch for automatically arresting the movement of said impulse-transmitter an invariable predetermined distance in advance to the end of its traverse, whereby a succession of impulses may be followed by an additional impulse, means acting in response to a succession of impulses for variably actuating said selector from its normal position and means acting in response to the additional impulse for effecting its return to normal.

40. The combination with a selector and with an operating-circuit therefor, of an impulse-transmitter for the selector-operating circuit, means for automatically arresting the movement of said impulse-transmitter at different points and in opposite electrical conditions, of a selector-operating magnet in said circuit the armature of which is correspondingly arrested in opposite electrical conditions and devices operated by said armature for effecting the variable movement of said selector from its normal position and for effecting its return thereto.

41. In a selective system for telephones, the combination with a selector and with an operating-circuit therefor, of an impulse-transmitter, an automatic switch for the telephone-circuit, means for variably actuating said impulse-transmitter, a shiftable stop controlled by the movement of said switch arranged automatically to arrest the operation of said impulse-transmitter before it has completed its traverse, whereby a succession of impulses may be followed by an additional impulse, an actuating-magnet for said selector, means operated by said magnet and acting in response to a succession of impulses for variably actuating said selector in one direction, means actuated by said magnet in response to the additional impulse for releasing said selector

to permit its return in the opposite direction to normal and a retractor for said selector.

42. In a selective system for telephones, a telephone having an automatic switch, a selector and an impulse-transmitter for the selector-operating circuit at each of the stations, means for variably actuating said impulse-transmitters, a stop connected to each of the telephone-switches for automatically arresting the movement of said impulse-transmitters in advance of the end of their traverse, whereby the succession of impulses may be followed by an additional impulse, an electromagnet at each station for propelling the selectors in one direction from normal position in response to a succession of impulses and governor-controlled means actuated by the armature of said magnet at each station for effecting the return of said selectors to normal in response to the additional impulse.

43. In a selective system for telephones, the combination with the telephone-circuit and with a selector, of an impulse-transmitter for the selector-operating circuit arranged to transmit a variable number of electrical impulses and an additional impulse, means acting in response to a succession of impulses for variably moving said selector in one direction from normal, means acting in response to the additional impulse to permit its return in the opposite direction to normal, a retractor for said selector and a lock-out for the telephone-circuit controlled by said selector.

44. A selective apparatus for telephones, the combination with a switch for the telephone-circuit, with a step-by-step selecting device and an operating-circuit therefor, of an impulse-transmitter for said selector-operating circuit, means for variably actuating said impulse-transmitter, means automatically operating to arrest the movement of said impulse-transmitter before and at the end of its traverse, whereby a succession of impulses is followed by an additional impulse, a magnet acting in response to said succession of impulses for variably actuating said selecting device from its normal position, means actuated by said magnet for releasing said selector to permit its return in the opposite direction to normal, a retractor for said selector, a lock for said telephone-switch and trips carried by said selecting device arranged to hold said lock out of operation, both in the normal position of said selecting device and after the movement thereof to a predetermined position.

45. In selective systems, the combination with a selector and with an operating-circuit therefor, of an impulse-transmitter for said circuit, means for variably actuating said impulse-transmitter, means automatically operating to arrest the movement of said impulse-transmitter an invariable predetermined distance in advance of and at the end of its trav-

erse, whereby a succession of impulses is followed by an additional impulse, an actuating-magnet for said selector, means operated by said magnet in response to the succession of 5 impulses for variably actuating said selector in one direction from normal, governor-controlled means actuated by said magnet for effecting the return of said selector in the opposite direction to normal and a signal controlled by the movement of said selector.

46. In selective systems, the combination with a selector and with an impulse-transmitter for the selector-operating circuit at each station, of means for variably actuating each 15 impulse-transmitter, means for arresting the operation of each transmitter both before and at the end of its traverse, whereby a succession of impulses is followed by an additional impulse, means at each station acting in response to a succession of impulses for variably 20 actuating said selecting devices in response to the succession of impulses, means acting in response to the additional impulse for effecting the return of said selecting devices to normal and means at each station controlled by the movement of the selecting device for preventing the initial movement of the impulse-transmitter when the line is in use.

47. In a selective apparatus, the combination 30 with a selector, an actuating-magnet therefor and an operating-circuit, of an impulse-transmitter for the selector-operating circuit, means for variably actuating said impulse-transmitter, means for arresting the operation of the impulse-transmitter before and at the end of its traverse, whereby a succession of impulses may be followed by an additional impulse, a step-by-step device actuated by said magnet in response to the succession 35 of impulses for advancing said selector in one direction, a retractor for returning said selector in the opposite direction to normal, means operated directly by the armature of said magnet in response to the additional impulse for tripping said retractor into operation and means for holding said trip out of operation during and at the end of the succession 45 of impulses.

48. In a selective apparatus, the combination 50 with a selector having a series of uniform ratchet-teeth, an actuating-magnet therefor and an operating-circuit, of an impulse-transmitter for the selector-operating circuit, means for variably actuating the impulse-transmitter, means for arresting the impulse-transmitter both before and at the end of its traverse whereby a succession of uniform impulses is followed by an additional impulse, a feed-pawl actuated by the armature of said 55 magnet in response to the succession of impulses for advancing said selector step by step in one direction, a retaining-pawl for said selector, a trip for said retaining-pawl, means operating to hold said trip out of operation 60 during and at the end of the succession of

electrical impulses and for actuating said trip in response to the additional impulse and a retractor for returning said selector in the opposite direction to normal.

49. In selective systems, the combination 70 with a selector having a series of uniform ratchet-teeth, an actuating-magnet therefor and an operating-circuit, of an impulse-transmitter for said circuit, means for variably actuating said impulse-transmitter, means for 75 arresting the movement of the latter both before and at the end of its traverse, whereby a series of uniform impulses is followed by an additional impulse, a step-by-step device actuated by said magnet in response to the succession of impulses for variably actuating said selector in one direction, a releasing-trip for said selector, means for coupling said releasing-trip directly to the armature of said magnet and means actuated by the armature 80 of said magnet during the succession of impulses for holding said coupler out of operation, said magnet being arranged to actuate said release-trip through the medium of said coupler in response to the additional impulse. 85

50. In selective systems, the combination with a selector, of an operating-circuit therefor, an impulse-transmitter for said circuit arranged to transmit a succession of impulses followed by an additional impulse, propelling 95 devices acting in response to a succession of impulses for advancing said selector from its normal position, governor-controlled means acting in response to the additional impulse for effecting the return of the selector to normal, said governor means comprising a freely-vibrating arm and means actuated by the operation of said propelling devices for holding said freely-vibrating arm out of operation. 100

51. In selective systems, the combination 105 with said selector and with an operating-circuit therefor, of an impulse-transmitter for said circuit, means for variably actuating said impulse-transmitter, means for arresting the operation of the latter both before and at the 110 end of its traverse whereby a succession of impulses is followed by an additional impulse, an actuating-magnet for said selector acting in response to the succession of impulses for advancing said selector from normal position, means 115 acting in response to the additional impulse for returning said selector to normal, and a governor for controlling said return-effecting means comprising a freely-vibrating arm and a freely-vibrating knocker interposed between 120 said arm and the armature of said magnet.

52. In selective systems, the combination 125 with a selector and with an operating-circuit therefor, of an impulse-transmitter for said circuit, means for variably actuating said impulse-transmitter, means for arresting the operation of said impulse-transmitter before and at the end of its traverse, whereby a succession of impulses is followed by an additional impulse, a propelling-magnet acting in 130

response to the succession of impulses for advancing said selector in one direction and governor-controlled means for effecting the return of said selector in the opposite direction to normal comprising an arm shiftable in different directions, the armature of said magnet being arranged to vibrate said arm in one direction during the succession of impulses to hold it out of operation and to shift said arm in another direction in response to the additional impulse to effect the return of said selector.

53. In selective systems, the combination with a selector and an operating-circuit therefor, of an impulse-transmitter for said circuit, means for variably actuating said impulse-transmitter, means for arresting its operation both before and at the end of its traverse, whereby a succession of impulses is followed by an additional impulse, a propelling-magnet for advancing said selector in one direction in response to the succession of impulses, devices for effecting the return of said selector in the opposite direction to normal, a vibrating arm normally coupling said return-effecting devices directly to the armature of said magnet and arranged to be operated by a single vibration thereof and means for holding said vibrating arm out of operation during the succession of impulses.

54. In a selective apparatus, the combination with a step-by-step selector and with an operating-circuit therefor, of power-propelled impulse-transmitter for the operating-circuit, means for variably actuating said impulse-transmitter, stop devices arranged to automatically arrest the operation of said transmitter both before and at the end of its traverse whereby a succession of impulses may be followed by an additional impulse, an actuating-magnet operating in response to the succession of impulses for operating said selector step by step in one direction, devices for effecting the return of said selector in the opposite direction to normal, a governor for controlling said return-effecting devices comprising a vibrating arm arranged to normally couple said return-effecting devices directly to the armature of said magnet and be operated by a single vibration thereof and means operated by the armature of said magnet for holding said coupling-arm out of operation during the successive vibrations thereof.

55. In a selective system for telephones, a telephone having an automatic switch, a selector and an impulse-transmitter for the selector-operating circuit at each of the stations, means acting in response to a succession of electrical impulses transmitted by any of the impulse-transmitters over the operating-circuit to actuate said selecting devices and means controlled by the telephone-switches for transmitting an additional impulse over the operating-circuit to return the selecting devices to normal position.

56. In a selective system for telephones, a telephone having an automatic switch, a selector and an impulse-transmitter for the selector-operating circuit at each of the stations, means actuated by the telephone-switch for controlling the movement of the impulse-transmitters whereby a succession of electrical impulses followed by an additional impulse may be transmitted over the selector-operating circuit, means acting in response to the succession of impulses for moving the selecting devices from the normal position and means acting in response to the additional impulse for releasing the same to permit their return in the opposite direction to normal. 80

57. In a selective system for telephones, a telephone having an actuating-switch, a selector and an impulse-transmitter for the selector-operating circuit at each of the stations, means for variably actuating said impulse-transmitters, shiftable stops controlled by the movement of the telephone-switch at each station for arresting the movement of the impulse-transmitter at such station in advance of the end of its traverse, whereby a succession of impulses, followed by an additional impulse, may be transmitted over the selector-operating circuit, an electromagnet at each station for said selectors acting in response to the succession of impulses for variably moving said selectors in one direction, governor-controlled means at each station directly operated by the armatures of said magnets for effecting the return of said selectors in the opposite direction to normal in response to the additional impulse and devices actuated by the armatures of said magnets for holding the governors out of operation during the succession of impulses. 95

58. In a selective system for telephones, a telephone having an automatic switch, a selector and an impulse-transmitter for the selector-operating circuit at each of the stations, means for variably actuating said impulse-transmitters, stop devices controlled by the movement of said telephone-switches for arresting the operation of said impulse-transmitters in advance to the end of their traverse whereby a succession of impulses, followed by an additional impulse, may be transmitted over the selector-operating circuit, a propelling-magnet at each station acting in response to the succession of impulses for variably actuating said selectors in one direction, devices for effecting the return of said selector in the opposite direction to normal, a vibrating governor-arm at each station arranged to normally couple said return-effecting device directly to the armatures of said actuating-magnets and be operated in response to the additional impulse and means actuated by the armature of said magnet for holding said coupling-governor-arm out of operation during the succession of impulses. 110 115 120 125

59. In selective systems for telephones, the

- combination with selectors and automatic switches for the telephone-circuit at different stations, of a lock for each switch, trips carried by each selector for holding said lock out 5 of operation both in the normal position and after the movement of said selector to a pre-determined point, an operating-circuit for said selectors, an impulse-transmitter for said circuit and means operating in response to a 10 succession of impulses transmitted by said impulse-transmitter for variably actuating each of said selectors.
60. In selective systems for telephones, the combination with an automatic switch for the 15 telephone-circuit and a signal at different stations, of variably-movable step-by-step selectors located at each of said stations, an operating-circuit therefor, an impulse-transmitter for said circuit, a lock for each of the 20 telephone-switches and means actuated by the variable movement of said selectors in response to impulses transmitted by said impulse-transmitter for controlling said lock and said signal.
- 25 61. In selective systems for telephones, the combination with an automatic switch for the telephone-circuit and with an electrical signal at different stations, of a selector at each of said stations, a selector-operating circuit, an 30 impulse-transmitter for said circuit, a lock for each of said switches, means for actuating said selector in response to impulses transmitted by said impulse-transmitter and a trip controlled by said selector for throwing said 35 lock out of operation and for closing the circuit through said signal after the movement of said selector to a predetermined distance.
62. In selective systems, the combination with a selector at each of a number of different 40 stations, of an operating-circuit for said selectors, an impulse-transmitter for said circuit at each of said stations, means for actuating said selectors in response to electrical impulses transmitted by any one of said 45 impulse-transmitters and mechanical connections between the selector and impulse-transmitter at each of said stations arranged to prevent the initial operation of said impulse-transmitter when the line is in use.
- 50 63. In selective systems, the combination with a telephone-switch and a selector at each of a number of different stations, of an operating-circuit for said selectors, an impulse-transmitter for said circuit at each of said stations, means for actuating said selectors in 55 response to impulses transmitted by any one of said impulse-transmitters, a shiftable locking-stop for the impulse-transmitter controlled by the telephone-switch at each of said 60 stations and means controlled by the selector at each station for preventing the removal of said stop when the line is in use.
64. In selective systems for telephones, the combination with an automatic switch for telephone-circuits and a selecting device at each 65 of the number of different stations, of an operating-circuit for said selecting devices an impulse-transmitter for said circuit at each of said stations, stops controlled by the movement of said switches for normally holding 70 said impulse-transmitters out of operation, means for actuating said selectors in response to impulses transmitted by any one of said impulse-transmitters and locks for said telephone-switches controlled by the movement 75 of said selectors.
65. In a selective system for telephones, the combination with several telephone-stations provided with telephones arranged upon a single line, of a selector-operating line having 80 in its circuit a variably-movable step-by-step selecting instrument at each of the stations and an impulse-transmitter arranged to impart a definite number of impulses in accordance with the station to be called, telephone- 85 switches for connecting each of the telephones to line and means controlled by the variable movement of said selecting instruments for locking the telephone-switches.
66. In a selective system for telephones, the combination with several stations provided with telephones arranged upon a single line, of a selector-operating line having in its circuit a variably-movable step-by-step selective 90 instrument at each of the stations, an impulse-transmitter for the selector-line arranged to impart thereto a definite number of impulses in accordance with the station to be called, automatic switches for connecting individual 95 telephones to the line-circuit and means for operating the selecting instruments acting in response to the succession of impulses transmitted to call any of the stations and to lock the telephone-switches at the remaining stations.
- 100 67. In selective systems for telephones, the combination with two or more telephone-stations provided with telephones arranged upon a single line, of an independent selector-operating line having in its circuit a selecting instrument and an impulse-transmitter at each 105 of the stations and means operated by the selecting instruments acting in response to a succession of impulses transmitted by any of the impulse-transmitters, to call one of the 110 stations and to prevent the completion of the telephone-circuit at the other stations.
68. In selective systems for telephones, the combination with two or more telephone-stations provided with telephones arranged upon a single line, of an independent selector-operating line, a step-by-step selector and an automatically-acting transmitter at each of the 120 stations, means acting in response to a succession of impulses transmitted by any of said impulse-transmitters to variably actuate said selector step by step, a call at each of said stations actuated by the selector at said station when moved to a predetermined point and a 125 lockout at each of said stations controlled di- 130

rectly by said step-by-step selector and actuated when any of the other stations is called.

69. In selective systems for telephones, the combination with two or more telephone-stations provided with telephones arranged upon a single line, of a selector at each of said stations, an independent selector-operating line having in its circuit an actuating-magnet for said selectors and an impulse-transmitter at each of said stations, means operated by said actuating-magnet in response to a succession of impulses interposed by any of the impulse-transmitters to actuate said selectors in one direction and call a predetermined one of said stations and means actuated by said magnets in response to an additional impulse transmitted by any of said impulse-transmitters to effect the return of said selectors in the opposite direction to normal.

70. In selective systems for telephones, the combination with several telephone-stations provided with telephones arranged upon a single line-circuit, of an independent selector-operating line having in its circuit a selecting instrument and an impulse-transmitter at each of the stations, an automatic telephone-switch, a lock for said switch and a signal at each of the stations, said lock and said signal being controlled by the selecting instruments acting in response to a succession of impulses transmitted by any of the impulse-transmitters, to call one of the stations and to lock the telephone-switches at the other stations.
